UNITED STATES PATENT OFFICE.

FRANK MILHENING, OF CHICAGO, ILLINOIS, ASSIGNOR TO J. MILHENING, INC., OF CHICAGO, ILLINOIS, A CORPORATION OF ILLINOIS.

DESIGN FOR A SETTING FOR A PRECIOUS STONE.

48,910.

Specification for Design.

Patented Apr. 18, 1916.

Application filed January 22, 1916. Serial No. 73,731. Term of patent 7 years.

To all whom it may concern:

Be it known that I, FRANK MILHENING, a citizen of the United States, residing in the city of Chicago, county of Cook, and State of Illinois, have invented a new, original, and ornamental Design for a Setting for a Precious Stone, of which the following is a specification, reference being had to the accompanying drawing, forming part thereof.

Figure 1 is a plan view of a setting for

precious stones, showing my new design; Fig. 2 is a side elevation of the same; Fig. 3 is a plan view of the bottom of the setting; and Fig. 4 is an enlarged sectional view on the line 4—4 of Fig. 1, looking in the direction of the arrows.

I claim:

The ornamental design for a setting for a precious stone, as shown.

FRANK MILHENING.
